Theodore Roffey, Toronto, Ontario, Canada

Application April 1, 1946, Serial No. 128,135
In Canada March 12, 1946

Term of patent 3½ years

(Cl. D74—1)

To all whom it may concern:

Be it known that I, Theodore Roffey, a subject of the King of Great Britain and resident of the city of Toronto, in the Province of Ontario, Dominion of Canada, have invented a new, original, and ornamental Design for a Combination Desk Unit, of which the following is a specification, reference being had to the accompanying drawing, forming part thereof.

Fig. 1 is a top perspective view of a combination desk unit showing my new design, and

Fig. 2 is a bottom perspective view thereof.

The essential features of my design reside in the parts shown in full lines.

I claim:

The ornamental design for a combination desk unit, as shown and described.

THEODORE ROFFEY.
